(57) **CLAIM**

The ornamental design for a tyre as shown.

DESCRIPTION

FIG. 1 is a front view of a tyre in accordance with our new design;

FIG. 2 is a perspective view thereof;

FIG. 3 is a right side view thereof; and,

FIG. 4 is a left side view thereof.

Applicant reserves the right to pursue one or more portions of the tyre shown herein in any combination, sub-combination, or combination of sub-combinations. For example, Applicant reserves the right to pursue any single view; any portion of any of the inner and/or outer treads/grooves; etc., in any combination, sub-combination, or combination of sub-combinations. Interior portions of the tyre need not necessarily form a part of the claimed design. Applicant specifically reserves the right to claim the tyre tread pattern (s) without the flanks of the tyre.
